UNITED STATES PATENT OFFICE.

CARLTON D. STEWART, OF BERKELEY, CALIFORNIA, ASSIGNOR TO ASSOCIATED
ENGINEERING AND SUPPLY COMPANY, OF SAN FRANCISCO, CALIFORNIA, A
CORPORATION OF CALIFORNIA.

FUEL-OIL-REGULATING SYSTEM.

1,314,161.

Specification of Letters Patent. Patented Aug. 26, 1919.

Application filed September 11, 1918. Serial No. 253,539.

To all whom it may concern:

Be it known that I, CARLTON D. STEWART, a citizen of the United States, residing at Berkeley, in the county of Alameda and State of California, have invented new and useful Improvements in Fuel-Oil-Regulating Systems, of which the following is a specification.

This invention relates to an apparatus for controlling and regulating the flow of fluid fuel and an atomizing medium to fluid fuel burners.

One object of my invention is to provide a fluid fuel and atomizing medium controller adapted to be operated by the draft operating mechanism, so as to insure the control of fuel and atomizing medium in correct relation to the draft.

Other objects and advantages will appear in the following more detailed description of the invention.

In the accompanying drawings; Figure 1 is a front elevation, in part, of a steam boiler, with an apparatus applied for controlling the fluid fuel and atomizing medium by the draft operating mechanism, in accordance with my invention; Fig. 2, a fragmentary side elevation thereof; Fig. 3 a central sectional view of one of the fuel and atomizing medium controlling devices; Fig. 4 a section on the line 4-4 of Fig. 3; Fig. 5 a section on the line 5-5 of Fig. 3; and Fig. 6 a section on the line 6-6 of Fig. 3.

As shown in Figs. 1 and 2, the construction may comprise generally, a boiler 1 having one or more furnace doors 2, each provided with a suitable fluid fuel burner 3, corresponding ash pit doors 4, a stack damper 5, fuel and atomizing medium controllers 6, and a fuel oil pump 7 for supplying fuel oil through a main pipe 8 and branch pipes 9 to each controller 6.

Steam for operating the oil pump 7 is supplied through the pipe 10 and said pipe 45 may also be connected to the controllers 6 for supplying steam for atomizing the fuel oil.

Each controller 6 supplies fuel oil to the corresponding burner 3 through a pipe 11, and atomizing steam through a pipe 12.

The ash pit doors 4 and the stack dampers 5 are operated by a main shaft 13 which may be actuated manually or automatically and the rotation of this shaft is adapted to operate the fuel controllers. 55

As shown in section in Figs. 3 to 6 of the drawings, each fuel controller 6 may comprise a casing having a chamber 14 connected to pipe 12 and a chamber 15 connected to pipe 11. 60

A chamber 16 in the casing is connected to steam pipe 10 and contains adjustable valves 17, 18, and 19. Valve 17 controls an orifice leading from chamber 16 to chamber 14, the valve 18, an orifice from chamber 16 to a valve chamber 20, and valve 19, an orifice leading from chamber 16 to a valve chamber 21. 65

Communication from valve chambers 20 and 21 to chamber 14 is controlled by the 70 respective valves 22 and 23, adapted to be operated by cams 24 and 25, carried by a shaft 26.

A chamber 27 in the casing is connected to the oil supply pipe 9 and contains adjustable valves 28, 29, and 30, the valve 28 controlling an orifice leading from chamber 27 to chamber 15, the valve 29, an orifice leading from chamber 27 to valve chamber 31, and valve 30, an orifice leading from 75 chamber 27 to valve chamber 32.

Communication from valve chambers 31 and 32 to chamber 15 is controlled by the respective valves 33 and 34, adapted to be operated by cams 35 and 36, carried by a 80 shaft 37.

The shafts 26 and 37 are adapted to be operated by levers 38 and 39 which are operatively connected, through a rod 40 and a lever 41, with the main shaft 13 so that 90 the movement of the shaft 13, to control the boiler dampers also operates to control the supply of fuel and atomizing medium to the burners.

In operation, when movement is transmitted to the damper shaft 13, in a direction adapted to open the ash pit doors 4 and the stack damper 5, the rod 40 is also actuated to shift the levers 38 and 39. The cam shafts 26 and 37 are then turned so as 95 100

to first bring the cams 24 and 35 into engagement with the valves 22 and 33, lifting the valves from their seats.

If the movement of the damper shaft 13 continues sufficiently in the same direction, cams 25 and 36 are brought into contact with the respective valves 23 and 34, lifting said valves from their seats.

The relative time of movement between cams 24 and 35, and also between the cams 25 and 36 is arranged to meet the desired conditions as to time of opening for the fuel and the atomizing medium valves, and likewise the time of movement of the cams 24 and 35 with respect to the time of movement of the cams 25 and 36 is regulated by adjusting the relative angularity of the two sets of cams by means of the turn-buckle 42.

20 Fuel oil under pressure from the oil pump 7 flows through the pipe 8 and branch pipe 9 to the chamber 27 of each controller 6 and outflow from this chamber is controlled by the valves 28, 29, and 30.

25 Fuel oil flowing past the valve 28 enters chamber 15, and thence flows through pipe 11 to the burner 3.

Fuel oil flowing past the valve 29 enters chamber 31 and oil flowing past the valve 30 enters chamber 32.

35 Steam for atomizing the fuel flows from steam pipe 10 to chamber 16 of the controller 6 and thence flows past the valves 17, 18 and 19 to the respective chambers 14, 20, and 21, steam supplied to chamber 14 flowing through pipe 12 to the burner 3.

If the damper operating shaft is rotated so as to open the ash pit doors and the stack dampers sufficiently to provide correct draft 40 for the largest fire, the rod 40 will be actuated so as to lift all the valves 22, 23, 33, and 34 from their seats, so that fuel oil from the chambers 31 and 32 can flow to chamber 15 and thence to the burner 3 as well as 45 atomizing steam from the chambers 20 and 21 to the chamber 14 which is connected to the burner 3, the above flow of oil and steam being in addition to that supplied directly through the valves 28 and 17.

50 When the steam in the boiler has reached the desired maximum pressure and it is desired to reduce the fire a certain amount, the damper shaft 13 is rotated in the direction tending to close the ash pit doors and 55 the damper. The first movement of the shaft 13 in this direction, causes the rotation of the cam shafts 26 and 37 and the arrangement of the cams is such that the valves 23 and 34 are first allowed to seat, 60 and the seating of these valves may occur simultaneously, or one before the other, as desired.

With the valves 23 and 34 seated, the fire is reduced a predetermined amount, and

further rotation of the shaft 13, causes the 65 ash pit doors and the stack damper to be closed the correct amount for the fire then burning.

If it is desired to reduce the fire still further, the shaft 13 is rotated farther in the 70 direction tending to close the dampers.

The valves 22 and 33 are then allowed to first seat and the further movement of the shaft 13 causes the further closing of the ash pit doors and the stack damper to correspond with the fire burning after the 75 valves 22 and 33 have been closed.

The fire remaining may be further reduced, if desired, by manually operating the valves 17 and 28, which control a direct supply 80 of fuel and steam to the burners.

The apparatus hereinbefore described may be adjusted so as to provide a direct gradual range from minimum to maximum, instead of the step-by-step range, by opening the 85 fuel valves 29 and 30 wide and also the atomizing medium valves 18 and 19.

The flow of fuel oil through the device will then be proportional to the opening created by the valves 33 and 34, as they are 90 moved on and off their seats by the cams 35 and 36.

The flow of atomizing medium will be proportional to the openings created by the valves 22 and 23, as they are moving on and 95 off their seats by the cams 24 and 25.

During the direct range of control from minimum to maximum, just described, the pilot fire fuel valve 28 and the pilot fire atomizing valve 17 provide for manually adjusting the degree of pilot fire desired.

It will now be seen that the apparatus is adapted to control the fire either step-by-step, or by a gradual range from maximum to minimum in proportion to the degree of 100 opening of the dampers.

It will also be evident that other forms of fuel may be employed instead of oil, such as powdered or pulverized fuel.

Having now described my invention, what 110 I claim as new and desire to secure by Letters Patent, is:

1. In a fuel oil regulating system, the combination with a damper operating mechanism, of different sets of valves for supplying fuel oil and atomizing medium and means operated by said damper controlling mechanism upon a predetermined movement thereof for actuating one set of valves and upon a further predetermined movement for 120 actuating another set of valves.

2. In a fuel oil regulating system, the combination with a damper operating mechanism, of a plurality of sets of valves for supplying fuel oil and atomizing medium, 125 shafts operated by said damper operating mechanism, and cams operated by said shafts for actuating one set of valves upon a pre-

determined movement of the damper operating mechanism and for actuating another set of valves upon a further movement of the damper operating mechanism.

5. 3. In a fuel oil regulating system, the combination with a damper operating mechanism, of a plurality of valves for supplying fuel oil and atomizing medium and means operated by the damper actuating

mechanism for operating said valves serially, to effect a step-by-step regulation of the flow of fuel oil and atomizing medium.

In testimony whereof I have hereunto set my hand.

CARLTON D. STEWART.
